MANUFACTURE OF URANIUM TETRACHLORIDE

Filed Nov. 30, 1944

UNITED STATES PATENT OFFICE

2,574,268

MANUFACTURE OF URANIUM
TETRACHLORIDE

Martin D. Kamen, Berkeley, Calif., assignor to
the United States of America as represented by
the United States Atomic Energy Commission

Application November 30, 1944, Serial No. 566,009

8 Claims. (Cl. 23—14.5)

1

This invention relates to the manufacture of uranium tetrachloride and more particularly to a process using trichloroacetylchloride and an oxide of uranium for the manufacture of uranium tetrachloride.

It is an object of this invention to provide an improved process of producing uranium tetrachloride of high chemical purity and in crystalline form.

Another object of the invention is to provide an improved trichloroacetylchloride and uranium oxide process of producing uranium tetrachloride in which the product is of uniform purity and side reactions productive of other uranium chlorides and other objectionable compounds are minimized.

Another object of the invention is to provide an improved process of producing uranium tetrachloride which involves a reaction of trichloroacetylchloride vapor with an oxide of uranium.

A general advance in the art and other objects which will appear hereinafter are also contemplated.

It has now been found that uranium tetrachloride can be prepared in high yield and high purity by maintaining a continuous flow of trichloroacetylchloride over a charge of uranium oxide (UO_2 , UO_3 , or U_3O_8) heated to a temperature within the range of 135° to 225° C. and as near 180° C. as practicable, the pressure being substantially atmospheric. It has also been found that an apparatus particularly suited to carry out this procedure comprises vaporizing and reaction chambers so connected and arranged that the trichloroacetylchloride vapors may be forced by gravity from the vaporizing chamber into the reaction chamber and the gaseous products formed in the reaction chamber are forced to exit through the vaporizing chamber.

How the foregoing objects and related ends are accomplished will be apparent from the following exposition in which are disclosed the principles, the organization, and divers embodiments of the invention, including the best mode contemplated for carrying out the same, all of which is amplified by the accompanying drawing in which suitable apparatus is shown diagrammatically. Proportions of reagents are specified as parts by weight throughout the written description.

Referring now to the single sheet of the drawing, there is shown a reaction vessel 3 connected to a condenser L which is in turn connected to a supply reservoir 2. An inner gas line C extends through the condenser and into the reaction vessel. The reaction vessel is shaped somewhat like

an hourglass and comprises a reaction chamber A and a vaporizing chamber B. These chambers are supported on sand bath heaters 5 and 6, respectively. The sand heater 5 is supported on a bracket 7 and the sand heater 6 is supported on a bracket 8. Both brackets are secured to the upright of a stand 9 which rests on the surface 11. At the other end of the apparatus the upright of a stand 12 supports a bracket 13 which in turn supports bracket 14 which in its turn, through a clamp 15, supports the elevated end of the condenser at which end is vent 4. The upright of the stand 12 also supports a bracket 16 to which is secured a clamp 17 which in turn supports the reservoir 2. Usually the reservoir 2 is graduated and has a gravity feed valve 18 whereby the rate at which the liquid reactant trichloroacetylchloride is being utilized can be regulated. A container for an inert gas under pressure (not shown) is connected at the upper end of the line C. The outer jacket E of the condenser has the usual inlet 19 and outlet 21 for a cooling fluid.

In operation the reaction chamber A is charged with uranium dioxide and the reaction vessel 3 connected to the condenser L. A gentle stream of inert gas such as nitrogen is flowed into the reaction chamber A through the line C to sweep out the air. The flow of inert gas continues throughout the reaction during which time it serves to sweep out by-product gases and excess trichloroacetylchloride vapor. Heat is then applied to the reaction chamber A to raise the temperature of the uranium oxide to 180° C. and said temperature is maintained while a flow of trichloroacetylchloride is started through the valve 18. This trichloroacetylchloride collects in the vaporizing vessel B. After a pool of the desired size has collected, heat is applied and the addition of trichloroacetylchloride from the reservoir 2 regulated to keep the liquid level in vessel B substantially constant. Upon the application of heat to the vaporizing chamber B some of the trichloroacetylchloride vapor that is evolved enters the condenser L and is refluxed. Another portion of the vapor flows by gravity into the reaction chamber where it reacts with the uranium dioxide, usually forming carbon monoxide, carbon dioxide, phosgene and chlorine. These gases are swept up into the condenser along with some trichloroacetylchloride vapor by means of the nitrogen entering through the line C. Some of the phosgene is dissolved in the trichloroacetylchloride and carried back into the reaction chamber where it reacts with the ura-

nium dioxide. The gases which are not condensed in the condenser are vented through the line 4, preferably into a suitable scrubber which may be of conventional design and operation.

During the process additional trichloroacetylchloride is supplied as it is consumed in the reaction with the charge of uranium oxide and the process is continued until all the charge of the uranium oxide has been converted to UCl_4 . At this time, i. e. when the reaction of the charge of uranium oxide is complete, the evolution of reaction gases ceases, thereby providing a ready indication of the completion of the process.

In carrying out the present process involving uranium dioxide in the production of uranium tetrachloride the reaction temperature should be maintained as near $180^\circ C$. as practical; however, satisfactory results may be obtained in the range of 135° to $225^\circ C$.

Substantially atmospheric pressure in the reaction zone is preferred, although elevated or reduced pressures are not objectionable and small pressure variations do not materially affect the yields or purity of the product.

The reaction is usually complete in less than five hours, the time depending to some extent on the crystalline form and particle size of the raw material, the temperature of the reaction, and the size of the charge. A reaction time of from two to five hours has been found suitable. Trichloroacetylchloride of ordinary commercial purity is satisfactory for the reaction. The process may be carried out in glass or metal apparatus.

Inert gases other than nitrogen may be utilized but in the case of materials like illuminating gas some pyrolysis may occur.

The present invention is particularly useful in the treatment of uranium trioxide since it provides a method for obtaining uranium tetrachloride instead of the pentachloride normally obtained.

After the uranium tetrachloride has been produced it may be removed from the reaction chamber in any desired manner, such as by removing the reaction chamber from the remainder of the apparatus and pouring the crystalline product therefrom. It should be transferred to a dry container and maintained in storage under an environment of a dry inert gas such as carbon dioxide, or in vacuum.

It may be noted that the uranium tetrachloride may frequently be associated with appreciable quantities of uranium pentachloride formed during the course of the main reaction. These two chlorides may, if desired, be separated in any suitable manner, such as by extraction with a selective solvent for one of them. Carbon tetrachloride is an example of a suitable solvent for this purpose, since it has a preferential solvent action towards the pentachloride. Any non-volatile impurities such as uranium oxychloride or unreacted uranium oxide still remaining in admixture with the uranium tetrachloride may be separated, if desired, by a step of sublimation wherein the desired tetrachloride is sublimed away from the associated non-volatile impurities.

The uranium tetrachloride produced in accordance with the present invention has a crystal size and structure especially suitable for sublimation or vaporization in vacuum apparatus. Its form allows it to be readily outgassed and there is little tendency for it to be transported as a dust while being processed in region of reduced pressure.

Many apparently widely different embodiments

of this invention may be made without departing from the principle, breadth and spirit thereof and it is to be understood therefore that this invention is not limited to the specific embodiments thereof except as encompassed in the claims.

What is claimed is:

1. A process of producing uranium tetrachloride comprising passing trichloroacetylchloride vapors over an oxide of uranium maintained at a temperature within the range of $135^\circ C$. to $225^\circ C$., and recovering the uranium tetrachloride.

10 2. The process of producing uranium tetrachloride comprising reacting uranium trioxide with trichloroacetylchloride vapor at a reaction temperature within the range of $135^\circ C$. to $225^\circ C$. in which the trichloroacetylchloride vapor is passed continuously over the reaction mass, and recovering the uranium tetrachloride.

15 3. The process comprising reacting trichloroacetylchloride vapor with uranium dioxide at a temperature of about $180^\circ C$. to produce uranium tetrachloride, and recovering the uranium tetrachloride.

20 4. The process of producing uranium tetrachloride containing some uranium pentachloride from an oxide of uranium comprising reacting said oxide with the vapors of trichloroacetylchloride at an elevated temperature of the order of $180^\circ C$. for a period of time in the range of two to five hours, and recovering the uranium tetrachloride.

25 5. The process of producing uranium tetrachloride comprising reacting trichloroacetylchloride with an oxide of uranium selected from the group consisting of UO_2 , UO_3 and U_3O_8 at a reaction temperature within the range of $135^\circ C$. to $225^\circ C$. and at substantially atmospheric pressure, and recovering the uranium tetrachloride.

30 6. A process comprising heating an oxide of uranium in contact with trichloroacetyl chloride to produce uranium tetrachloride, and recovering said uranium tetrachloride.

35 7. The process comprising reacting an oxide of uranium with trichloroacetyl chloride in the vapor phase to produce uranium tetrachloride, and recovering said uranium tetrachloride.

40 8. The process comprising, reacting trichloroacetyl chloride vapor with an oxide of uranium selected from the group consisting of UO_2 , UO_3 and U_3O_8 at a reaction temperature of about $180^\circ C$. and in the presence of an inert gas while at atmospheric pressure to produce uranium tetrachloride of high quality and having a crystal size and form suitable for processing in an evacuated system.

45 9. The process comprising reacting trichloroacetyl chloride vapor with an oxide of uranium selected from the group consisting of UO_2 , UO_3 and U_3O_8 at a reaction temperature of about $180^\circ C$. and in the presence of an inert gas while at atmospheric pressure to produce uranium tetrachloride of high quality and having a crystal size and form suitable for processing in an evacuated system.

50 10. The process comprising reacting trichloroacetyl chloride vapor with an oxide of uranium selected from the group consisting of UO_2 , UO_3 and U_3O_8 at a reaction temperature of about $180^\circ C$. and in the presence of an inert gas while at atmospheric pressure to produce uranium tetrachloride of high quality and having a crystal size and form suitable for processing in an evacuated system.

55 11. The process comprising reacting trichloroacetyl chloride vapor with an oxide of uranium selected from the group consisting of UO_2 , UO_3 and U_3O_8 at a reaction temperature of about $180^\circ C$. and in the presence of an inert gas while at atmospheric pressure to produce uranium tetrachloride of high quality and having a crystal size and form suitable for processing in an evacuated system.
